UNITED STATES PATENT OFFICE.

GEORGE T. CLARK, OF OLD ORCHARD, MAINE, ASSIGNOR TO SACO-LOWELL SHOPS, OF BOSTON, MASSACHUSETTS, A CORPORATION OF MASSACHUSETTS.

STRAIGHTENING MACHINE.

Application filed April 13, 1921. Serial No. 460,863.

To all whom it may concern:

Be it known that I, GEORGE T. CLARK, a citizen of the United States, residing at Old Orchard, in the county of York and State of Maine, have invented certain Improvements in Straightening Machines, of which the following description, in connection with the accompanying drawings, is a specification, like reference characters on the drawings indicating like parts in the several figures.

This invention relates to machines for straightening rods, bars, spindles, shafts, and similar articles, and it will be disclosed herein as embodied in a machine designed especially for straightening the spindles used in spinning machines.

Spindles of this type usually have tapered ends and in manufacturing them it is customary to cut off a piece of steel rod of the required length and then forge this piece of stock to approximately the desired taper, thus forming what is known as a spindle blank. Usually these blanks cool off in a bent or crooked condition and before they can be ground to the exact taper and size desired it is necessary to straighten them. If these blanks are straightened while they are cold they will, nevertheless, have a certain tendency to return to their crooked or bent condition; and while this tendency may be dormant, so to speak, or at least insufficient to produce any distortion of the spindle while it is at rest, still when it is run at the high speed at which these spindles are now customarily operated, this speed, together with the vibration of the machine, allows this unbalanced molecular condition to assert itself and produces an excessive vibration of the spindle. For this reason it is preferable to perform the straightening operation while the spindles are hot enough to overcome any molecular set or biased condition which the spindles otherwise might have.

It is the chief object of the present invention to devise a straightening machine for spindles and similar articles which shall be simple in construction, economical to manufacture, which shall be to a large degree automatic in operation, in which the dies can readily be adjusted to the contour of the article to be straightened, and which generally shall satisfy the practical requirements of a machine of this character.

The nature of the invention will be readily understood from the following description when read in connection with the accompanying drawings, and the novel features will be particularly pointed out in the appended claims.

Referring now to the drawings,

Figure 1 is a side elevation of a machine constructed in accordance with the present invention;

Fig. 2 is a front elevation of the machine shown in Fig. 1;

Fig. 3 is a cross sectional view showing the mechanism for adjusting the length of stroke of the dies;

Fig. 4 is a vertical cross sectional view through the dies and adjacent parts;

Fig. 5 is a plan view of the parts shown in Fig. 4 with the upper die cut away;

Fig. 6 is a view partly in side elevation and partly in cross section of a counting mechanism that determines the number of strokes to be given to each spindle;

Fig. 7 is a cross sectional view of a detail of the counting mechanism; and

Fig. 8 is a cross sectional view through the lower die and the adjacent parts.

Briefly stated, the machine shown comprises a lower and an upper die, mechanism for reciprocating the upper die to roll the spindle between the two dies, a counting mechanism that determines the number of reciprocations which the upper die shall make while acting on a given spindle and which controls a mechanism that raises the upper die when the straightening operation on the spindle has been completed, and a work gage for facilitating the positioning of the work between the dies. The detailed description of these mechanisms will be taken up in substantially the order in which they have just been mentioned.

Referring especially to Figs. 4, 5 and 8, it will be seen that the lower die is made in two sections, indicated at A and B, and that each section comprises a series of bars 3 secured by screws to a base 4. The bars preferably are made of steel and the base 4 consists of a steel or iron plate of sufficient thickness to be comparatively rigid so that it will hold the bars in properly spaced relationship while still thin enough to permit it to be flexed or sprung. Both the sections A and B are secured to a rigid bed 5 by means of clamps having horizontal arms 6

which enter notches cut in the ends of certain of the bars 3. Each clamp includes a screw 7 which extends vertically through a flange that projects from the bed 5 and is threaded into the arm 6 so that it is operative to draw the bars 3 down toward the bed 5 with great force. Shims 8, Fig. 8, are placed between the base 4 and the bed 5 at the proper points to enable the clamps to bend or spring the base 4 sufficiently to give the desired contour to the die surface formed by the upper edges of the series of bars.

It will be seen from an inspection of Fig. 8 that the spindle S has a long taper at its right-hand end and a much shorter taper at its left-hand end. At the stage of the process of manufacture in which the straightening operation is performed these end portions do not have a true tapered shape but are bulged or bowed. Consequently, the base members 4 are not straight plates resting in an inclined plane but are each sprung or bent downwardly. It will be understood, however, that the degree to which each base plate is sprung or bent will depend on the contour which it is desired to give to the upper surface of the die, this contour being complementary to that of the part of the work which rests on it.

In making dies of this character the bars 3 are secured to the base 4 by screws, or in any other convenient manner, and the upper surfaces of the bars are then ground off to form substantially a true plane. By using die sections of appropriate length and shims of the proper height these dies can be bent or sprung to produce a great variety of tapers, curvatures or contours. It will readily be appreciated that it is a relatively expensive matter to make solid dies having surfaces of the character here required. The construction here provided, therefore, has the very important advantage of being economical to manufacture and also of being adjustable to fit a great variety of spindles or similar articles. It therefore effects a very material saving in manufacturing costs.

The lower die is mounted in a water pan 10 of substantial construction which is secured on the upper end of a bracket 11, Figs. 1 and 2, mounted for adjustment in vertical ways 12 and supported by a post 13, the lower end of which is threaded into a block 14 mounted on an extension from the base of the machine. A hand wheel 15 is secured to this post and serves as a convenient means for adjusting the height of the lower die.

Water is continuously supplied to the pan 10 by a hose or pipe connection and is maintained at a predetermined height by an overflow 16, Fig. 8, leading to a waste pipe 17. This arrangement keeps the lower die cool.

The upper die comprises a series of rela-

tively heavy bars or arms 19 each having a hardened piece 20, Fig. 4, secured to its lower surface by bolts 21-21. The lower surfaces of these bars 20 engage the work and these surfaces therefore are slightly rounded as shown in Fig. 8.

For the purpose of reciprocating the upper die, the entire series of bars 19 is mounted on a shaft 23, Fig. 4, which is secured at its opposite ends in links 24-24' that form part of a parallel motion mechanism. That is, one end of the right-hand link 24 is pivoted to the upper end of an arm 25 mounted fast on a rock shaft 26 that is supported in bearings formed in the opposite sides of the machine frame, while the other end of the link is pivoted to the lower end of an arm 27 secured fast on another rock shaft 28 that extends through the frame from side to side. The left-hand link 24' is mounted in the same manner. The shaft 28 projects through the left-hand side of the machine, as shown in Fig. 2, and has an arm 30 secured fast to its projecting end. This arm is pivoted to the upper end of a pitman rod 31, Figs. 1 and 2, the lower end of said rod being pivoted on a crank pin 32 projecting from a disk 33 which is keyed to the main shaft 34. A pulley 35 mounted on this shaft may be belted to any convenient source of power for the purpose of driving the machine.

It will now be understood that when the main shaft 34 is rotating the connections just described will cause the bars 19 to reciprocate backward and forward in a horizontal plane and thus will impart a rolling motion to the spindle S, Fig. 4, positioned between the upper and lower dies. For the purpose of adjusting the length of this stroke the arm 30, Figs. 1, 2 and 3, is embraced by a U-shaped block 36 between the lower legs of which the pitman rod 31 is pivoted, and this arm has depending lugs at opposite sides of the block 36 through which adjusting screws 37 and 38 are threaded, these screws bearing on pieces 39-39 secured to the opposite sides of the block. By turning these screws in the proper directions the block 36 may be moved toward or from the axis of the rock shaft 28, thus decreasing or increasing the angular movement imparted to the rock shaft by the pitman 31, and consequently adjusting the stroke of the upper die. A screw 40 threaded through the upper part of the member 36 bears against the arm 30 and serves to take up any lost motion that otherwise might occur between the block and the arm.

It is desirable that the work engaging faces of the bars 20 shall be parallel at all times to the corresponding faces of the bars of the lower die, since otherwise the reciprocating motion would tend to squeeze the spindle out from between the dies. Consequently, provision is made for the vertical

adjustment individually of the bars composing the upper die. For this purpose the left-hand end, Fig. 4 of each bar 19 is bored to receive a circular projection 41 extending laterally from one face of a gear or toothed disk 42, and this member is mounted eccentrically on the shaft 23, as clearly shown in Fig. 4. A flat spring 43 is bolted to the upper surface of each bar 19 and has a tooth 44 which extends between the teeth of the gear 42 and locks this gear against rotation. This spring also has an up-turned portion 45 forming a thumb piece by means of which the free end of the spring may be lifted 15 to disengage the tooth 44 from the gear 42. When it is desired to raise or lower one of the bars 19 it is merely necessary to disengage the tooth 44 from the gear 42 and then rotate this gear by hand in the proper 20 direction to raise or lower the bar the required degree. The spring is then released, allowing the tooth 44 to engage the gear again and hold the gear and its eccentric 41 in the newly adjusted position.

25 The upper and lower dies should be so adjusted that as the spindle S is rolled backward and forward between them the axis of the spindle S, Fig. 4, will travel in substantially a horizontal plane. In Fig. 5 the bars 30 19 of the upper die are shown in the relative spaced relationship to the bars of the lower die which naturally would be used, it being understood that these bars can be spaced as desired on the rock shaft 23 by the 35 use of suitable spacing collars, or in any other convenient manner. The bars 19 simply rest on the spindle, each bar taking its position independently of its neighbor. In other words, the upper die which is composed of these bars conforms automatically 40 to the contour of the spindle or other article of work which it engages.

45 The machine also includes means for automatically raising the upper die out of co-operative relationship to the lower die when the straightening operation on a given spindle has been completed. For this purpose the bars 19 which constitute the upper die are connected by straps 48 to a cross 50 piece or rod 49, Figs. 1 and 2, which is supported in the forward ends of two arms 50--50 both secured fast to a rock shaft 51 mounted in bearings in the machine frame. Each of the arms 50 has a bracket 52 secured thereto (see Fig. 6) which is connected by a 55 pivot pin 53 with the upper end of a plunger 54 mounted in a cylinder 55. The lower end of this cylinder is provided with a ball end 56 which is supported in a suitable socket 60 formed in a bracket 57 secured fast to the machine frame. Compressed air supplied through a pipe 58 and connections 60 with the cylinders 55 may be admitted to lower 65 ends of the cylinders to raise the plungers 54--54 and thus operate through the con-

nnections above described to raise the upper die, the supply of air to the cylinders being controlled by an air valve 61, Fig. 6. The movement of each plunger 54 relatively to its cylinder 55 is limited by a pin 62, Fig. 6, 70 projecting through a slot 63 formed in the cylinder.

Normally the air valve 60 is maintained in its closed position so that the cylinders 55--55 are open to the atmosphere and the 75 plungers 54--54 are held at the lower limits of their movement by the weight of the parts that they support. During this time the upper die rests in contact with the lower die or on the spindle or other article of work 80 placed between the dies. The air valve 60 is under the control of a counting mechanism which can be adjusted to predetermine the number of strokes that will be given to each spindle. This mechanism comprises a pitman rod 65, Figs. 1, 2 and 6, mounted at its lower end on a pin 66 projecting eccentrically from the end of the main shaft 34, the upper end of this rod being guided in a slot 85 formed in a bracket 67 that is secured to the top of the machine frame. A pawl 68 secured to this pitman rod is operative normally to engage the teeth of a rack 69, best shown in Fig. 6, which is mounted to slide vertically in a guideway formed in the machine frame. A strap 70 connected to the upper end of the rack 69 runs over a pulley 71 and is connected at its opposite end to the stem 72, Fig. 7, of a piston 73 fitting loosely within a long tube or pipe 74 that 100 contains oil or other liquid. This tube is secured to the frame by upper and lower brackets 75 and 76, respectively, Fig. 2. The back or left-hand edge, Fig. 6, of the rack 69 is smooth and an arm 77 which is secured 105 to the valve operating lever 78 is normally held firmly against this edge of the rack by a strong spring 79. The pressure thus exerted by the arm 77 on the rack is sufficient 110 to hold the rack in any adjusted position in its guideway. Consequently, as the pitman rod 65 is reciprocated by the rotation of the shaft 34, the pawl 68 will raise the rack tooth by tooth and the rack will be held 115 against backward movement during the idle stroke of the pawl by the pressure exerted by the spring 79.

While the arm 77 is resting against the rack 69 it holds the air valve lever 78 in the position shown in Fig. 6 with the valve 120 61 closed; but when the pawl 68 raises the lower end of the rack clear of the arm 77 the spring 79 immediately swings the lever 78 about its fulcrum 80, thus causing the short arm of this lever to depress the valve pin 81 125 thereby opening the valve and admitting compressed air from the supply pipe 82 to the cylinders 55--55. The plungers 54 are immediately raised, thus lifting the upper die in the manner above described. 130

This action also produces a clock-wise rotative movement of the rock shaft 51, as seen in Fig. 6, and this movement brings a cam 83 on the rock shaft 51 into contact with an arm 84 mounted fast on a rock shaft 85. Another arm 86 also secured to the rock shaft 85 has a finger 87 which, at this time, engages the left-hand side, Fig. 6, of the pitman rod 65, and swings this rod toward the right far enough to move the pawl 68 out of engagement with the rack 69 and thus stop any further upward movement of the rack. The parts remain in this position with the upper die raised well above the lower die where it affords free access to the lower die and thus give the workman ample room to place a spindle in position between the dies.

When it is desired to lower the upper die into cooperative relationship to the lower die again the workman grasps the handle 90 of the lever 78 and pulls it toward the front of the machine thus moving the arm 77 out from under the rack 69, whereupon this rack drops under the influence of gravity until it strikes a spring-supported stop 91 mounted on a collar 92 which is adjustable vertically on the pipe or tube 74. The stop 91 preferably is made of rubber, leather, or the like, and its vertical adjustment determines the initial height of the rack and, consequently, the number of teeth that the rack must be moved by the pawl 68 before the upper die will be raised automatically away from the work. Since this rack is raised one tooth at each reciprocation of the upper die, it is a very simple matter to predetermine the number of strokes that will be given to each spindle.

When the rack 69 is dropped in the manner above described, the piston 73 retards the movement of the rack and thus reduces the shock that otherwise would be produced.

The movement of the arm 77 from under the lower end of the rack 69 closes the valve 61, and releases the air in the cylinder 55, thus allowing the upper die to descend slowly until the bars 19 rest on the work. The rotative movement of the rock shaft 51 produced in this manner releases the arm 84 from the control of the cam 83 and thus allows the pitman rod 65, Fig. 6, to swing toward the left until the pawl 68 engages the teeth of the rack again, this movement of the pitman rod being produced by a weight 93, Figs. 1 and 2, which is secured to the pitman. This restores the parts of the counting mechanism to their initial positions and the operations above described are then repeated.

The movement of the lever 90 which is produced by the spring 79 is limited by a stop 94, Fig. 6, formed on a bracket which is secured to a part of the machine frame

by set screws or bolts 95 and which also carries an adjusting screw 95' to facilitate the adjustment of the stop relatively to the lever.

It is important in using the machine that the spindles be placed in the proper angular position between the dies, and for this purpose a work gage is provided which can also be used as an ejector. This gage comprises plates 96—96, Fig. 5, secured in spaced relationship to bars 97—97. Four members 98 are secured in pairs to these plates to engage and center the spindle, and the longitudinal position of the spindle is determined by an end abutment 99. The gage 96 rests on the upper surface of two brackets 100—100, Figs. 1 and 2, secured to the water pan 10 at opposite sides thereof. In order to hold this gage in the proper angular relationship to the guides, it is pivotally connected at each side to the upper end of a rod 101 that slides in a tube 102 which is secured at its lower end to a rock shaft 103 supported in brackets 104 secured to the slide or bracket 11. A handle 105, Fig. 2, is connected to the left-hand rod 102 and enables the attendant to swing the work gage backward and forward, the telescoping connection just described permitting this movement but holding the gage against swinging in a horizontal plane. Stops 106 secured to the opposite ends of each bracket 100 limit the movement of the gage.

It will be seen that when this gage is moved forward to the limit of its stroke 100 it will carry the spindle S off the lower die and over an inclined apron 107, Figs. 1 and 4. This apron, being below the level of the die, will allow the spindle to drop through the gage and the spindle will then roll down the apron into a box 108, Fig. 1, which receives the straightened spindles. The operator next moves the gage back to about the middle of the lower side in readiness to receive another spindle.

The machine shown, as will be evident from an inspection of Fig. 1, is of the duplex type. That is, the dies, counting mechanism and other parts are duplicated at the left-hand side of the machine, both upper dies, however, being driven by a single mechanism. These duplicate parts have not been illustrated since such illustration obviously is not necessary to a proper disclosure of the invention.

In using the machine the workman heats the spindles in a conveniently located furnace, usually keeping several spindles heating at the same time. He places one of these spindles, which has been heated up to about a cherry red, in the position indicated at S, Fig. 5, the upper die at this time being in its raised or inoperative position. The workman then moves the lever 90 to lower the upper die, in the manner 130

above described, and the reciprocating motion of the upper die rolls the spindle back and forth between the dies. During this movement the spindle carries the work gage 5 96 to and fro with it. The bars constituting the upper dies are very heavy and, since the spindle is hot, this rolling motion effectually straightens the spindle. The lower die is partially submerged in water, as above 10 19 described, and consequently it cools the spindle rapidly enough to give it a fairly hard temper while, or immediately after, it has been straightened and while it is still being rolled between the dies. This rolling 15 motion is continued until the spindle is so cold that there is no danger of its becoming bent or warped again, and after it has been given a number of strokes predetermined by the counting mechanism, the upper die is 20 raised automatically, as previously described, and the workman then grasps the handle 105 and moves the work gage 96 forward to effect the ejecting of the spindle. In the meantime, while this straightening 25 operation has been going on, the workman has placed another spindle in the other side of the machine and this spindle is being subjected to the straightening action of the dies. The machine thus is automatic to a 30 very large degree and the greater part of the workman's time and attention, therefore, can be given to the heating of the spindles.

It will now be appreciated that the invention 35 provides a machine of very simple but sturdy and substantial construction, in which the depreciation is very slow, which is convenient to operate, and in which, due to the nature of the dies, a great variety of 40 articles can be straightened with a relatively few dies.

In using the machine it is evident that the spindle is stopped momentarily at each end of its stroke. It is therefore subjected 45 during these periods of rest to the weight of the upper die, and it would naturally be supposed that the length of the stroke should be so adjusted that the spindle would stop either in the same angular position at 50 the opposite ends of its stroke, or else that its angular position at one end of the stroke should be diametrically opposite that at the other end. I find, however, that this does not produce the best results, and that at 55 least in the straightening of spindles very much better results are produced by stopping the rotation of the spindle at some intermediate angular position at opposite ends of the stroke instead of at the same or diametrically opposite angular positions. 60 Usually the adjustment is made such that the spindle is stopped at one end of its stroke in an angular position about 90° different from that in which it is stopped at the opposite end of its stroke. This

particular angular relationship, however, is not absolutely essential, but it is preferable to so adjust the stroke that the angular position of the spindle at one end of the stroke shall be substantially different from 70 either the same or a diametrically opposite position from that in which it is stopped at the opposite end of the stroke. The process of straightening which involves this angular relationship of the spindle at the 75 opposite ends of its stroke is not claimed herein but will be claimed in another application.

While the invention has been herein described in connection with the hot 80 straightening of spindles, it will readily be appreciated that the machine can also be used successfully in the straightening of many other articles. Furthermore, it is contemplated that in some cases it will not 85 be necessary to heat the articles to be straightened but that they can be successfully straightened in this machine at normal temperatures. It will also be understood that while I have herein shown and de- 90 scribed the best embodiment of the invention of which I am at present aware, this embodiment may be modified in many particulars without departing from the spirit 95 or scope of this invention.

Having thus described my invention what I desire to claim as new is:

1. A straightening machine comprising, in combination, a lower die having a rigid work supporting face, an upper die comprising a plurality of independent bars arranged to bear on the article to be straightened to press it against said lower die, and means for relatively reciprocating said dies in a direction substantially parallel to said bars to rotate the article to be straightened between the dies. 100

2. A straightening machine comprising, in combination, a lower die having a rigid work engaging face, an upper die comprising a plurality of bars independently movable to bear on the work, whereby said upper die is conformable automatically to the contour of the work, means for relatively reciprocating said dies to roll the 110 work between them, and mechanism for raising and lowering said upper die to move it into or out of cooperative relationship to the lower die. 115

3. A straightening machine comprising, in combination, upper and lower dies, means for relatively reciprocating said dies to roll the article to be straightened between them, said upper die comprising a plurality of independent bars to bear on said article, a 120 strap connected to each bar, and mechanism acting through said straps to raise and lower said bars. 125

4. A straightening machine comprising, in combination, upper and lower dies, means 130

for relatively reciprocating said dies to roll the article to be straightened between them, said upper die comprising a plurality of independent bars to bear on said article, and a pneumatic mechanism for raising and lowering said bars.

5. A straightening machine comprising, in combination, a lower die having a rigid work engaging face, an upper die comprising a plurality of bars independently movable to bear on the work, whereby said upper die is conformable automatically to the contour of the work, means for relatively reciprocating said dies to roll the work between them, and mechanism for raising said bars out of cooperative relationship to the lower die comprising a power operated member and independent connections between said member and said bars.

20. 6. A straightening machine comprising, in combination, upper and lower dies, said upper die comprising a plurality of independent bars, a parallel motion mechanism for reciprocating the upper die to cause said dies to roll the article to be straightened between them, and means whereby the length of stroke of said upper die may be adjusted.

7. A straightening machine comprising, in combination, upper and lower dies, means for relatively reciprocating said dies to roll the article to be straightened between them, and adjustable mechanism for predetermining the number of said relative reciprocations to which each of said articles will be subjected.

8. A straightening machine comprising, in combination, upper and lower dies, mechanism for relatively reciprocating said dies to roll an article to be straightened between them, adjustable mechanism for predetermining the number of strokes to be given to said article, and mechanism operative automatically to effect a relative movement of said dies out of cooperative relationship when said number of strokes has been completed.

9. A straightening machine comprising, in combination, upper and lower dies, mechanism for relatively reciprocating said dies to roll an article to be straightened between them, adjustable mechanism for predetermining the number of strokes to be given to said article, and mechanism for automatically raising the upper die when the desired number of strokes has been completed.

10. A straightening machine comprising, in combination, upper and lower dies, means for relatively reciprocating said dies to roll an article to be straightened between them, and a gage operative to constantly control the position of said article between said dies during the straightening operation.

11. A straightening machine comprising, in combination, upper and lower dies, means

for relatively reciprocating said dies to roll the article to be straightened between them, a work positioning gage mounted between said dies, and means supporting said gage for movement in the direction of said reciprocating movement but holding the gage in a constant angular relationship to the dies during said movement.

12. A straightening machine comprising, in combination, upper and lower dies, means for relatively reciprocating said dies to roll the article to be straightened between them, a gage for holding said article in a predetermined angular relationship to said dies, and supporting means for said gage enabling it to be moved to and fro between the dies by said article.

13. A straightening machine comprising, in combination, upper and lower dies, means for relatively reciprocating said dies to roll the article to be straightened between them, and a combined work positioning gage and ejector mounted between said dies.

14. A straightening machine comprising, in combination, upper and lower dies, said upper die comprising a plurality of independent bars to bear on said article, means for relatively reciprocating said dies in a direction substantially parallel to said bars to rotate the article to be straightened between the dies, and means whereby said bars may be adjusted individually toward or from the lower die.

15. A straightening machine comprising, in combination, upper and lower dies, means for relatively reciprocating said dies to roll the article to be straightened between them, said upper die comprising a plurality of independent bars to bear on said article, means whereby said bars may be adjusted individually toward or from the lower die, and means whereby said lower die may be adjusted bodily toward or from the upper die.

16. In a straightening machine, a die comprising a series of bars, a base to which said bars are rigidly secured, said base supporting said bars in spaced relationship but being adapted to be flexed under heavy pressure, and means for bending said base and holding it in a bent condition to give the desired contour to the die surface formed by the upper edges of said bars.

17. In a straightening machine, a die comprising a series of bars, a base to which said bars are rigidly secured, said base supporting said bars in spaced relationship but being adapted to be flexed under heavy pressure, a rigid bed, and means for clamping said base to said bed and bending said base to give the desired contour to the die surface formed by the upper edges of said bars.

18. In a straightening machine, a die comprising a series of bars, a base to which

- said bars are rigidly secured, said base supporting said bars in spaced relationship but being adapted to be flexed under heavy pressure, a rigid bed on which said base is supported, shims between said bed and said base, and means for clamping said base to said bed and bending the base to give the desired contour to the die surface formed by the upper edges of said bars.
- 10 19. A straightening machine comprising, in combination, upper and lower dies, means for relatively reciprocating said dies to roll an article to be straightened between them, a pawl and ratchet mechanism operated in a fixed time relationship to said means, and means controlled by said mechanism for effecting a relative movement of said dies out of cooperative relationship when they have made a predetermined number of said 20 relative reciprocations.
- 20 20. A straightening machine comprising, in combination, upper and lower dies, means for relatively reciprocating said dies to roll an article to be straightened between them, a pawl and ratchet mechanism operated in a fixed time relationship to said means, an air valve controlled by said mechanism, and pneumatic means under the control of said valve for relatively moving said dies out of
- cooperating relationship when they have made a predetermined number of said relative reciprocations.
21. A straightening machine comprising, in combination, upper and lower dies, means for relatively reciprocating said dies to roll an article to be straightened between them, and mechanism for automatically interrupting the operation of said dies on said article when the article has been subjected to a predetermined straightening action. 40
22. A straightening machine comprising, in combination, upper and lower dies, means for relatively reciprocating said dies to roll an article to be straightened between them, and a gage having parts for engaging opposite sides of said article and thereby constantly controlling the position of said article during the straightening operation. 45
23. A straightening machine comprising, in combination, upper and lower dies, and mechanism for relatively reciprocating said dies to roll the work between them, said mechanism including means for enabling the length of the relative stroke of said dies to be adjusted. 50
- 55 In testimony whereof I have signed my name to this specification.

GEORGE T. CLARK.
